FLUORESCENT LIGHT FIXTURE

Peter De Mauro, Whitestone, N.Y., assignor to Globe Lighting Products, Inc., Brooklyn, N.Y., a corporation of New York

Application August 22, 1957, Serial No. 679,727

14 Claims. (Cl. 240—51.11)

The present invention relates to fluorescent light fixtures and is more particularly directed toward a fluorescent light fixture constructed so as to permit access to the interior of the fixture in a quick, simple and efficient manner without necessitating the use of any tools whatsoever.

According to the present invention, the fluorescent light fixture is provided with two light diffusing members constituting the closure for the light outlet opening of the fixture, said diffusing members being mounted for pivotal movement about pins on the socket plates and being retained in their normally closed position by a retaining member. By merely moving the retaining members to a retracted position thereof, the diffusing members automatically swing outwardly thus permitting quick access to the lamps inside the fixture.

According to another aspect of the present invention, the fluorescent light fixture is provided with two socket plates adjacent the end plates of the fixture. Said socket plates are of such construction as to enable them to support the light diffusing members, act as a light baffle, and constitute a housing for the wiring from the sockets to the ballast housing.

One object of the present invention is the provision of a fluorescent light fixture of improved construction so as to permit access to the interior thereof in a quick, simple and efficient manner without necessitating the use of any tools.

Another object of the invention is to provide a fluorescent light fixture, having a light outlet opening, the closure for which comprises two light diffusing members pivotally mounted so as to freely swing outwardly when the retaining member therefor is retracted, so as to permit access to the interior of the light fixture.

Another object of the invention is to provide in a fluorescent light fixture socket plates of an improved construction, said socket plates having provision for pivotally mounting and supporting the light diffusing members, for housing the wires from the sockets to the ballast housing, and said socket plates also acting as baffles to prevent escape of the light outside of said light diffusing members.

The above and other objects, features and advantages of the present invention will be more fully understood from the following description of the presently preferred embodiment of the invention, considered in connection with the accompanying illustrative drawings.

In the drawings:

Fig. 1 is a perspective view of the fluorescent light fixture according to the present invention;

Fig. 2 is a top plan view of one end portion of the fixture looking in the direction of arrow 2 in Fig. 1, with parts broken away for purposes of illustration;

Fig. 3 is a cross-section taken along line 3—3 of Fig. 2;

Fig. 4 is a cross-section taken along line 4—4 of Fig. 2 showing the diffusing members in open position;

Fig. 5 is a transverse section taken along the line 5—5 of Fig. 3;

2

Fig. 6 is a perspective view of one of the end plates of the fixture;

Fig. 7 is a perspective view of one of the socket plates of the fixture; and

Fig. 8 is a partial sectional view similar to Fig. 3 and showing a modified form of the present invention.

Referring now to Figure 1 of the drawings there is shown a fluorescent light fixture 10 provided with end plates 12, light pervious diffusing members 14 constituting the closure for the light outlet opening of the fixture, and a retaining member 16 engaging adjacent portions of light diffusing members 14 for supporting said members in position to close said light outlet opening of the fixture. Said light diffusion members 14 are preferably molded of a suitable plastic but may be made of glass, and are comparatively stiff. As seen in Figure 4, retaining member 16 is movable to a retracted position whereby light diffusing members 14 are released and are free to swing outwardly and downwardly under the force of gravity, away from each other, thereby automatically opening said light outlet opening of the fixture to permit access to the interior thereof, as will be described hereinafter in greater detail.

As stated above fixture 10 is provided at each end thereof with an end plate 12. Each end plate (Fig. 6) has upper inwardly extending spaced flanges 18, each of said flanges being provided with a hole 20 for mounting the ballast housing of said fixture. End plate 12 may also be provided with a conventional knockout 22, as shown.

A socket plate 24 is provided adjacent each end plate 12 of the fixture 10, and as best seen in Fig. 7, said socket plate comprises a substantially peripherally and outwardly flanged member having an outer contour of similar configuration as that of end plate 12 but being of slightly smaller dimension than the latter. Socket plate 24 is provided with upper outwardly extending spaced flanges 26, the upper surface of said flanges abutting the lower surface of flanges 18 of end plates 12 as best seen in Fig. 5, cut-outs 28, ears 30 having holes 32, inwardly extending horizontal tabs 34 having holes 36, and inwardly extending vertical tabs 38 having holes 40. Openings 42 are provided on said socket plate for mounting fluorescent lamp sockets, and a T-shaped recess 44 is provided centrally of said socket plate.

The ballast housing for lamp fixture 10 comprises an inverted open bottom longitudinally extending channel 46 which is secured at each end thereof to end plate 12 and socket plate 24. Toward that end, upper wall 48 of channel 46 is provided near each end thereof with spaced holes 50 which are in alignment with holes 20 on end plates 12, and said channel is secured to said end plates by any suitable means such as threaded studs 52 and nuts 54. As seen in Fig. 3, side walls 56 of channel 46 are in surface-to-surface relation with tabs 38 of socket plate 24, and are provided with holes 58 in alignment with holes 40 of said tabs. The side walls 56 may thus be secured to socket plate 24 by any suitable means such as threaded studs 60 and nuts 62. It will be understood that the position of holes 40 in socket plates 24, holes 20 in end plates 12, and holes 50, 58 in channel 46 are so related that when securing of said channel to said plates is effectuated the outwardly extending peripheral flanges of socket plate 24 will be in abutting relation with the inner surface of end plate 12 and the upper surface of socket plate flanges 26 will abut lower surface of end plate flanges 18, as best shown in Fig. 5.

It will be observed that legs 56 of channel 46 extend in the longitudinal direction only up to socket plate 24 while upper wall 48 of said channel extends longitudinally through the recess 44 in socket plate 24 up to the inside surface of the end plates. Upper wall of channel 46 is

provided with a conventional knockout (not shown) for passage of the wiring from the ceiling to the ballast housing and said upper wall is also provided with conventional means for supporting the fixture from the ceiling.

Conventional fluorescent lamp sockets 64 are mounted in openings 42 for supporting fluorescent lamps 66. The wiring from sockets 64 passes through the space 68 between socket plate 24 and end plate 12 and extends into the ballast housing through recess 44 in the socket plate. Thus it is seen that socket plate 24, being spaced from the end plate 12, cooperates with the latter to provide a housing for the wiring. Bracing members 70 extend longitudinally of the fixture between the socket plates and are secured at their ends, respectively, to the adjacent tabs 34 of socket plates 24.

A ballast housing cover 72 is longitudinally co-extensive with channel 46 and comprises upper vertical sidewall portions 74, downwardly sloping sidewall portions 76 and bottom horizontal wall 78. As best shown in Fig. 4, complementary holes 80 and 82 are provided on channel 46 and cover 72, respectively, for releasably securing said cover onto the channel. An inverted U-shaped leaf spring 84 is provided with legs 86 having outwardly extending pins 88 and 90. Spring 84 biases legs 86 against sidewalls 56 of the channel whereby lower pins 90 engage holes 80 and 82 of channel 46 and cover 72, respectively. Upper pins 88 extend through holes 92 in channel 46 positioned above the upper edge of the cover. Said upper pins 88 are relatively larger than lower pins 90 and may easily be pushed inwardly in order to disengage lower pins 90 from holes 80 and 82, thereby releasing the ballast housing cover from the channel. Sidewalls 74 may be outwardly recessed directly above holes 82 as at 93, to provide a finger grip in order to facilitate removal of the ballast housing cover. It will be apparent that two of such leaf springs are sufficient for releasably securing the ballast cover to the housing though more may be utilized if so desired.

As shown in Figs. 2, 3 and 4, each socket plate 24 mounts two pivot pins 94, said pins being mounted in holes 32 of ears 30 in said socket plate for supporting light diffuser members 14 as will hereinafter be described. Each of said light diffuser members 14 extends longitudinally of fixture 10 between the end plates 12 thereof leaving only a small clearance as shown at 96 in Fig. 2 between the respective ends of the diffuser member and the end plate adjacent thereto.

With reference to Fig. 4 it will be seen that each diffuser member 14 has an upper portion 14a terminating in a bearing part 15 and a main or body part 14b terminating in the lower straight portion 14c which is slightly sloped outwardly of said main part. Diffuser members 14 are freely suspended on pins 94, upper portions 14a pivotally and slidably engaging the upper peripheral surface of said pins, and each of said members is thus pivotally movable about said pins. Cutouts 28 are provided in socket plate 24 for the movement of parts 15 of said diffusing members during the pivotal movement thereof.

Diffusing members 14 are held in their normally closed position as shown in Figs. 1 and 3 by means of a V-shaped retaining member 16 which extends longitudinally of fixture 10 between the end plates thereof. Spaced brackets 98 are secured to the inner side of retaining member 16, as by welding, each mounting an upwardly extending rod member 100, the upper end of which has a threaded opening engaged by a screw 102. Rods 100 extend through aligned apertures 104 provided therefor in bottom wall 78 of housing cover 72, said rods being grooved as at 106 for engagement with spring fingers 108 mounted on said housing cover for retaining member 16 in its uppermost position as shown in Figs. 1 and 5. Retaining member 16 is outwardly recessed adjacent said rods as at 110 to provide finger grips for facilitating retraction of said retaining member. Thus it is seen that retaining member 16 may easily be retracted from its uppermost position

(Figs. 1 and 5) to its lowermost position (Fig. 4), spring fingers 108 retaining said member in the upward position, and said fingers being disengaged from groove 106 when said retaining member is pulled to the retracted position thereof. The head of screw 102 is larger than the space between spring fingers 108 and therefore limits the downward movement of said retaining member, as seen in Fig. 4.

With retaining member 16 in its retracted position, 10 diffuser members 14 are pivoted inwardly about pins 94 bringing the lower portions thereof upwardly from the position shown in Fig. 4 to that shown in Fig. 3, and retaining member 16 is now moved to its uppermost position to engage the lower adjacent portions of diffuser members 14 and retaining the latter in fixed position between said retaining member and housing cover 72. It will be noted with reference to Fig. 3 that diffuser members are in engaging relation with both retaining member 16 and ballast housing cover 72, thus preventing any 15 vertical movement thereof so long as said retaining member remains fixed in said uppermost position. It is further apparent that retaining member 16 also acts as a light baffle to prevent the light from escaping through the space between the lower end portions of the diffuser members.

It will be noted that the shape of diffusing members 14 is complementary to the contour of socket plates 24 and accordingly, as best shown in Fig. 2, the flange portions of the socket plates provide a backing for the side edges of the diffuser members and also act as a light baffle to prevent the light from escaping through the clearance 96 between the end plates and the diffuser members.

It will be evident that while the fixture described above 35 is of substantially triangular configuration, it is within the scope of this invention to provide a light fixture embodying the above described features but having a different configuration. With reference to Fig. 8, it will be noted that the configuration of the fixture is substantially 40 rectangular. Toward that end, end plates 12' and socket plates 24' are of substantially rectangular configuration, as shown, and said plates are in all other respects identical with end plates 12 and socket plates 24, previously described in connection with Figs. 1-7. Also, light diffusing members 17 have a shape complementary to that 45 of said socket plates, the flanges of socket plates 24' providing a backing for the light diffusing members 17 when the latter are in the closing position thereof as shown.

From the above description it will be apparent that the 50 fluorescent light fixture of the present invention is of such construction that access to the interior of said fixture may be had in a quick and simple manner without the requirement of any tools and without the necessity of unfastening any fastening devices.

To gain access to the interior of the fixture in order 55 to replace the lamps, it is merely sufficient to grasp retaining member 16 at the finger grips 110 (Fig. 1) and lower it; light diffuser members will pivot outwardly and downwardly about pins 94 under gravity bias thus exposing fluorescent lamps 66 which may then be replaced. If 60 desired, light diffuser members 14 may be removed for cleaning by simply disengaging the upper hooked portions thereof from pins 94. The interior of the ballast housing is likewise easily accessible by merely pushing pins 88 inwardly, thus enabling ballast housing cover 72 to be 65 readily removed. It will be apparent that the fixture 10 may be reassembled with equal ease by merely performing the above described steps in reverse order.

Thus it is seen that the light fixture described above 70 with reference to the accompanying drawings, is well adapted to accomplish the objects of the present invention. It will be understood, however, that various changes may be made in the illustrated preferred embodiment of the invention without departing from the underlying idea of this invention. Accordingly I do not wish to be lim-

ited precisely to the form of the invention herein shown or described except as will be required by the scope of the claims.

Having thus described my invention, what I claim and desire to secure by Letters Patent is:

1. A light fixture comprising, a longitudinally extending lamp housing having a bottom light outlet opening and an end plate at each opposite end of said housing, a socket plate fixedly mounted on said housing at each end thereof inwardly of the adjacent end plate, inwardly extending pivot pins mounted at the upper corners, respectively, of said socket plates, closure means for said light outlet opening comprising a pair of light diffusing members extending longitudinally of said housing between said end plates, each of said closure members having a curved hooked portion extending along one side edge thereof, said curved hooked portion resting on and being pivotally supported by said pivot pins for pivotal movement under gravity bias from a position in which they close said light outlet opening and in which the lower edges of said members are in confronting relation to a position in which said members are laterally spaced from each other and depend from said pins and open said light outlet opening for providing access to the interior of said housing, and vertically retractable means carried by said housing for releasably engaging adjacent portions of said members for supporting said members when the latter are in the closing position thereof, said last mentioned means being movable vertically downward to a retractable position in which said members are released from engagement therewith and move by said gravity bias away from each other to the opening position thereof.

2. A light fixture comprising, a longitudinally extending lamp housing having a bottom light outlet opening and an end plate at each opposite end of said housing, a socket plate mounted on said housing at each end thereof inwardly of the adjacent end plate, each of said socket plates having an outwardly extending peripheral flange the outer edge of which abuts the inner surface of the adjacent end plate, inwardly extending pivot pins mounted at the upper corners, respectively, of said socket plates, closure means for said light outlet opening comprising a pair of light diffusing members extending longitudinally of said housing between said end plates, said closure members having upper side portions pivotally supported by said pivot pins and being pivotable from a position in which they close said light outlet opening and in which the lower edges of said members are in confronting relation to a position in which said members are laterally spaced from each other and depend from said pins and open said light outlet opening for providing access to the interior of said housing, and retractable means carried by said housing for releasably engaging adjacent portions of said members for supporting said members when the latter are in the closing position thereof, said last mentioned means being movable to a retractable position in which said members are released from engagement therewith and move away from each other to the opening position thereof, said socket plate flanges providing a backing for the ends of said members.

3. A fluorescent light fixture having a light outlet opening, said fixture comprising, a longitudinally extending inverted channel for mounting ballasts for said fixture, a cover for said channel coextensive therewith, means for detachably securing said cover to said channel including a resilient member disposed within said channel and having pins in engagement with said cover, a socket plate and an end plate secured to said channel at each end thereof, closure means for said light outlet opening comprising a pair of light pervious members each extending longitudinally of the fixture between the end plates thereof, support means carried by said socket plates for pivotally supporting said members at the upper side portions thereof, said members being movable from a position in which they close said light outlet

opening and in which the lower edges of said members are in confronting relation to a position in which said members are laterally spaced from each other and depend from said support means and open said light outlet

5 opening for providing access to the interior of said housing, and a retaining member carried by said channel cover and coextensive therewith and releasably engaging adjacent portions of said light pervious members for supporting said members when the latter are in the closing position thereof, said retaining member being movable to a retractable position in which said members are released from engagement therewith and move away from each other to the opening position thereof.

4. A fluorescent light fixture having a light outlet opening, said fixture comprising a longitudinally extending inverted channel for mounting ballasts for said fixture, a cover for said channel coextensive therewith and detachably secured thereto, a socket plate and an end plate secured to said channel at each end thereof, each of said socket plates being disposed inwardly of the adjacent end plate and having an outwardly extending peripheral flange abutting the inner surface of said adjacent end plate, closure means for said light outlet opening comprising a pair of light pervious members each extending longitudinally of the fixture between the end plates thereof, support means carried by said socket plates for pivotally supporting said members at the upper side portions thereof, said members being movable from a position in which they close said light outlet opening and in which the lower edges of said members are in confronting relation to a position in which said members are laterally spaced from each other and depend from said support means and open said light outlet opening for providing access to the interior of said housing, and a retaining member carried by said channel cover and coextensive therewith and releasably engaging adjacent portions of said light pervious members for supporting said members when the latter are in the closing position thereof, said retaining member being movable to a retractable position in which said members are released from engagement therewith and move away from each other to the opening position thereof, said support means comprising inwardly extending pivot pins mounted at the upper corners, respectively, of said socket plates, and said socket plate flanges supporting the ends of said members when the latter are in the closing position thereof.

5. A fluorescent light fixture having a light outlet opening, said fixture comprising, a longitudinally extending inverted channel for mounting ballasts for said fixture, a cover for said channel coextensive therewith, means for detachably securing said cover to said channel including a resilient member disposed within said channel and having pins in engagement with said cover, a socket plate and an end plate secured to said channel at each end thereof, closure means for said light outlet opening comprising a pair of light pervious members each extending longitudinally of the fixture between the end plates thereof, support means carried by said socket plates for pivotally supporting said members, said members being detachably supported on said support means at the upper side portions thereof, said members being movable from a position in which they close said light outlet opening and in which the lower edges of said members are in confronting relation to a position in which said members are laterally spaced from each other and depend from said support means and open said light outlet opening for providing access to the interior of said housing, and a retaining member carried by said channel cover and co-extensive therewith and releasably engaging adjacent portions of said members at one side thereof for supporting said light pervious members when the latter are in the closing position thereof, the other side 75 of said adjacent portions abutting said cover for fixedly

supporting said light pervious members in said closing position, said retaining member being movable to a retractable position in which said members are released from engagement therewith and move away from each other to the opening position thereof.

6. A fluorescent light fixture having a light outlet opening, said fixture comprising, a longitudinally extending inverted channel for mounting ballasts for said fixture, a cover for said channel coextensive therewith and detachably secured thereto, a socket plate and an end plate secured to said channel at each end thereof, each of said socket plates being disposed inwardly of the adjacent end plate in parallel spaced relation therewith, lamp sockets mounted on said socket plates, the space between each of said socket plates and the adjacent end plate defining a conduit for the wiring from said sockets to said ballasts, closure means for said light outlet opening comprising a pair of light pervious members each extending longitudinally of the fixture between the end plates thereof, support means carried by said socket plates for pivotally supporting said members at the upper side portions thereof, said members being movable by gravity bias from a position in which they close said light outlet opening and in which the lower edges of said members are in confronting relation to a position in which said members are laterally spaced from each other and depend from said support means and open said light outlet opening for providing access to the interior of said housing, and a retaining member carried by said channel cover and coextensive therewith and releasably engaging adjacent portions of said light pervious members for supporting said members when the latter are in the closing position thereof against said gravity biased movement, said retaining member being movable in a single downward movement to a retractable position in which said members are released from engagement therewith and move away from each other due to said gravity bias to the opening position thereof.

7. A fluorescent light fixture having a light outlet opening, said fixture comprising, a longitudinally extending inverted channel for mounting ballasts for said fixture, a cover for said channel coextensive therewith and detachably secured thereto, a socket plate and an end plate secured to said channel at each end thereof, each of said socket plates being disposed inwardly of the adjacent end plate in parallel spaced relation therewith and having an outwardly extending peripheral flange abutting the inner surface of the adjacent end plate, lamp sockets mounted on said socket plates, the space between each of said socket plates and the adjacent end plate defining a conduit for the wiring from said sockets to said ballasts, closure means for said light outlet opening comprising a pair of light pervious members each extending longitudinally of the fixture between the end plates thereof, support means carried by said socket plates for pivotally supporting said members at the upper side portions thereof, said members being movable from a position in which they close said light outlet opening and in which the lower edges of said members are in confronting relation to a position in which said members are laterally spaced from each other and depend from said support means and open said light outlet opening for providing access to the interior of said housing, and a retaining member carried by said channel cover and coextensive therewith and releasably engaging adjacent portions of said light pervious members for supporting said members when the latter are in the closing position thereof, said retaining member being movable to a retractable position in which said members are released from engagement therewith and move away from each other to the opening position thereof, said support means comprising inwardly extending pivot pins mounted at the upper corners, respectively, of said socket plates, and said socket plate

flanges supporting the ends of said members when the latter are in the closing position thereof.

8. A light fixture, comprising a frame having opposite end members and means associated therewith for supporting a tube-light therebetween, and having a light outlet opening, and a light diffusion cover for said opening, said light diffusion cover comprising a pair of light permeable cover members extending between said end members and pivotally supported thereby for movement to and from closed and open positions, each of said end members being fixed and having a pair of laterally spaced bearing supports in registry with a similar pair of bearing supports on the other of said end members, and each of said cover members having curved hooked portions resting on and pivotally supported by one of said bearing supports of each end member and swingable thereon under gravity bias from a closed substantially horizontal position downwardly to an open substantially vertical position, and releasable means engageable with said cover members for releasably holding these members in said closed position thereof to prevent the gravity biased swinging movement thereof to said open position.

9. A light fixture, comprising a frame having fixed opposite end members and means associated therewith for supporting a tube-light therebetween, and having a light outlet opening, and a light diffusion cover for said opening, said light diffusion cover comprising a pair of light permeable cover members extending between said end members and pivotally supported thereby for gravity biased movement to and from closed and open positions, each of said end members having a pair of laterally spaced bearing supports in registry with a similar pair of bearing supports on the other of said end members, and each of said cover members having curved hooked portions resting on and pivotally supported by one of said bearing supports of each end member and swingable thereon from a closed substantially horizontal position downwardly to an open substantially vertical position, and means carried by said frame for releasably holding said cover members in said closed position thereof, against said gravity bias, said curved hooked portions being removable from said bearing supports by lifting said cover member therefrom in a single upward movement, said end members having flanges providing a backing for the ends of said cover members.

10. A light fixture comprising, a lamp housing provided with a light outlet opening, closure means for said light outlet opening comprising a pair of light diffusing members, each of said light diffusing members having its center of gravity positioned to permit gravity biased movement of said light diffusing members from a closed position to an open position, each of said light diffusing members having a curved hooked portion extending along one side edge thereof, said housing having means for pivotally mounting each of said light diffusing members along said curved hooked portion thereof to permit said gravity biased pivotal movement of said light diffusing members from said closed position in which said light diffusing members cover said light outlet opening and in which the lower portions of each of said light diffusing members are in confronting relation to said open position in which each of said light diffusing members are laterally spaced from each other and depend from said mounting means to provide access to the interior of said housing, and means carried by said housing for releasably engaging adjacent portions of said light diffusing members for supporting said members in said closed position thereof to prevent said gravity biased movement of said members.

11. A light fixture comprising, a lamp housing provided with a light outlet opening, closure means for said light outlet opening comprising a pair of light diffusing members, each of said light diffusing members having its center of gravity positioned to permit gravity biased movement of said light diffusing members from a closed

position to an open position, said housing having means for pivotally mounting each of said light diffusing members at an upper part thereof for said gravity biased pivotal movement of said light diffusing members from said closed position in which said light diffusing members cover said light outlet opening and in which the lower portions of each of said light diffusing members are in confronting relation to said open position in which each of said light diffusing members are laterally spaced from each other and depend from said mounting means to provide access to the interior of said housing, said mounting means for each of said light diffusing members comprising a pair of pivot pins extending inwardly from each end of said lamp housing and means carried by said housing for releasably engaging adjacent portions of said light diffusing members for supporting said members in said closed position thereof to prevent said gravity biased movement of said members, said last mentioned means comprising a pin mounted for vertical sliding movement in said lamp housing and having portions for engaging each of said light diffusing members at said lower portions thereof, and resilient members on said lamp housing engageable with said pin in said closed position of said light diffusing members for releasably retaining said pin in said position.

12. A light fixture comprising, a lamp housing having a light outlet opening and oppositely disposed end members, each of said end members having a flange portion, closure means for said light outlet opening comprising a pair of light diffusing members extending between said end members with the ends of each of said light diffusing members being in abutting relation with said flange portions externally thereof in the closed condition of said light fixture to prevent the escape of said light from the ends of each of said diffusing members, each of said light diffusing members having its center of gravity positioned to permit gravity biased movement of said light diffusing members from said closed position to an open position, each of said light diffusing members having a curved hooked portion extending along one side edge thereof, said housing having means for pivotally mounting each of said light diffusing members along said curved hooked portion thereof to permit said gravity biased pivotal movement of said light diffusing members from said closed position in which said light diffusing members cover said light outlet opening and in which the lower portions of each of said light diffusing members are in confronting relation to said open position in which each of said light diffusing members are laterally spaced from each other and depend from said mounting means to provide access to the interior of said housing, and means carried by said housing for releasably engaging adjacent portions of said light diffusing members for supporting said members in said closed position thereof to prevent said gravity biased movement of said members.

13. A light fixture comprising, a lamp housing provided with a light outlet opening and oppositely disposed end members, closure means for said light outlet opening comprising a pair of light diffusing members extending between said end members, each of said light diffusing members having a curved hooked portion extending along one side edge thereof, each of said end members being provided with a pair of inwardly extending pins for pivot-

ally mounting each of said light diffusing members along said curved hooked portions to permit the gravity biased pivotal movement of said light diffusing members from a closed position in which said light diffusing members cover said light outlet opening and in which the lower portions of each of said light diffusing members are in confronting relation to an open position in which each of said light diffusing members are laterally spaced from each other and depend from said pivot pins to provide access to the interior of said housing, each of said light diffusing members having its center of gravity positioned to permit said gravity biased movement of said light diffusing members on said pivot pins from said closed position to said open position, and means carried by said housing for releasably engaging adjacent portions of said light diffusing members for supporting said members in said closed position thereof to prevent said gravity biased movement of said members.

14. A light fixture comprising, a lamp housing provided with a light outlet opening and oppositely disposed end members, closure means for said light outlet opening comprising a pair of light diffusing members extending between said end members, each of said light diffusing members having a curved hooked portion extending along one side edge thereof, each of said end members being provided with a pair of inwardly extending pins for pivotally mounting each of said light diffusing members along said curved hooked portions to permit the gravity biased pivotal movement of said light diffusing members from a closed position in which said light diffusing members cover said light outlet opening and in which the lower portions of each of said light diffusing members are in confronting relation to an open position in which each of said light diffusing members are laterally spaced from each other and depend from said pivot pins to provide access to the interior of said housing, each of said light diffusing members having its center of gravity positioned to permit said gravity biased movement of said light diffusing members on said pivot pins from said closed position to said open position, and means carried by said housing for releasably engaging adjacent portions of said light diffusing members for supporting said members in said closed position thereof to prevent said gravity biased movement of said members, said last mentioned means comprising a pin mounted for vertical sliding movement in said lamp housing and having portions for engaging each of said light diffusing members at said lower portions thereof, and resilient members on said lamp housing engageable with said pin in said closed position of said light diffusing members for releasably retaining said pin in said position.
